UNITED STATES PATENT OFFICE.

JOHN W. SMITH, OF NEW BRITAIN, CONNECTICUT, ASSIGNOR TO THE FAFNIR BEARING COMPANY, OF NEW BRITAIN, CONNECTICUT, A CORPORATION OF CONNECTICUT.

LAPPING MACHINE.

Application filed December 4, 1920, Serial No. 428,222. Renewed November 21, 1924.

To all whom it may concern:

Be it known that I, JOHN W. SMITH, a citizen of the United States of America, residing at New Britain, Hartford County, 5 Connecticut, have invented a new and useful Lapping Machine, of which the following is a specification.

My invention relates to a machine for grinding or lapping, and is particularly 10 adapted for grinding or lapping parallel surfaces on articles, but is not limited to use on articles requiring parallel surfaces.

It is an object of my invention to provide 15 a machine for lapping or grinding surfaces which will perform its function and produce a finished product of a high degree of accuracy and uniformity. In general, the object is to improve and simplify the construction of grinding or lapping machines. 20 Other objects and advantages will appear as the specification proceeds.

In the preferred form of my invention there is provided a pair of lapping discs mounted upon any suitable type of frame. 25

A work carrier is interposed between the discs. The carrier is provided with means 30 for holding a plurality of articles to be lapped. A means is provided to impart to the carrier a unique movement relatively to said discs whereby the articles in the carrier will be lapped down to uniform dimensions.

In the drawings, which show a preferred 35 form of machine for the purpose of illustration only—

Figure 1 is a central vertical sectional view of a machine embodying features of my invention; and

Fig. 2 is a section taken substantially in the plane of the line 2—2 of Fig. 1.

In said drawing, 5 represents any suitable 40 design of frame for supporting the parts of my machine. The upper part 6 of the frame supports one of the lapping or grinding discs 7. Mounted opposite the disc 7 and spaced therefrom is a complementary grinding or lapping disc 8. For the purpose of separating these discs I have shown means in the form of chains 9, secured to the disc 8, for raising the latter and separating the same from the disc 7. The discs 7 and 8 are preferably non-rotatably mounted on the frame. In order to prevent the disc 8 from rotating I have shown an apertured bar 10, adapted to fit over projecting pins 11 on the

frame. Obviously, and other suitable means 55 for preventing rotation and also for separating the discs may be provided.

A carrier for articles to be lapped is provided between the discs. In the form shown, a carrier 12, in the form of a relatively thin 60 disc, is provided with a plurality of apertures 13 therein for receiving articles to be lapped, such, for example, as bushings. The carrier is preferably of greater diameter than the discs. In order to space the carrier from the discs I have shown lips or flanges 14, turned down adjacent the apertures, and these flanges serve to space the main body of said carrier away from the lower disc to better hold the articles to be 70 lapped.

Extending through one of the annular discs is a shaft 15, having a crank 16 thereon. This crank 16 passes through or is otherwise secured to the carrier, preferably 75 at the center of the latter. A cap 17 may be provided above the crank, for preventing abrasive material from entering the crank bearing.

When the apertures in the carrier are 80 much larger than the size of the articles to be lapped, spacer elements, such as discs 18, may be provided to hold the articles away from the center of the apertures. This will prevent the articles from remaining in one 85 position relatively to the carrier. These spacer elements are preferably thinner than the articles being lapped and, if very thin, may be spaced away from one of the discs in any suitable manner, as by means of flanges 90 similar to the flanges 14 on the carrier.

In order to provide a means for introducing an abrasive substance between the discs and the articles to be lapped, I have indicated the upper surface of the upper disc 95 as provided with grooves 20, in which an abrasive mixture, such as emery and oil, may be poured. A series of apertures 21 extends from the bottoms of the grooves and through the disc in order to permit the introduction 100 of the abrasive between the lower surface of the upper disc and the articles to be lapped. The abrasive will pass down and enter between the articles and the upper surface of the lower disc. The excess abrasive 105 will fall between one of the discs and the upstanding flange 23 on a part of the frame. The abrasive passing over the inner edge of

the annular discs will find its way into the reservoir or container 24, and the abrasive mixture from these two containers may be received through pipes 25 and 26.

5 Due to the relative size and positioning of the carrier and discs and of the eccentricity of the crank shaft, some or all of the articles carried by the carrier will at some time during the lapping operation overlap both the 10 outside and inside edges of the annular discs, as indicated at 27, 28. This slight overlapping of the discs by some or all of the articles to be lapped insures an even and uniform wearing down of the lapping 15 surfaces of said discs and prevents formation of a shoulder or ridge thereon thus maintaining a true surface.

The operation of the machine is as follows:

20 The plates 7 and 8 are separated and the articles to be lapped, for example, rings 19, are introduced into the carriers. The spacer 18 if used is placed within the apertures in the carrier to prevent the articles from moving about too freely or remaining at the center. When a plurality of articles are placed 25 in a single aperture they are preferably loosely arranged within the same to permit an interchange or shifting about of the articles from a position adjacent the spacer to a position adjacent the edge of the aperture. This interchange will prevent some articles 30 from receiving more of the abrasive action than others. The heavy plate is then lowered onto the articles and an abrasive mixture, such as emery and oil, is introduced between the discs and the surfaces of the articles. The shaft 15 is next rotated, as by 35 means of a pulley 30.

40 The carrier is what may be termed a floating disc or carrier, for the latter is not constrained to move in a predetermined definite path. The center is, of course, constrained to move in a circle with the crank 16, but 45 other parts of the carrier may have very different and erratic motions. As a matter of fact, it has been found in practice that, upon rotation of the crank, parts of the carrier will of course have an oscillating movement or a movement substantially radial to the discs, without moving around the center of the same while at other times the carrier will actually rotate relatively to the discs in one direction or the other. It has also 50 been found that the articles, when loosely disposed in the apertures will shift around therein and will also tend to rotate about their own axes during their movement within the apertures. The motions given to the 55 articles being lapped, while not absolutely definite and predetermined, will, in general, be a movement in and out and around the discs relatively to the center thereof, and the individual articles will likewise turn and 60 shift circumferentially within the apertures 65

in the carrier. With the movements as indicated, each article being lapped traverses, or may traverse in the course of the lapping operation, substantially the entire surface of the lapping discs, both radially and circumferentially, and a highly accurate and uniform product is produced.

70 While I have shown the discs as substantially horizontally mounted I do not necessarily wish to have it understood that all 75 claims are limited to that arrangement.

While I have shown and described the machine as a lapping machine, I wish it to be understood that either one or both of the lapping discs might be replaced by discs 80 having inherent abrasive qualities and that my invention is broad enough to include grinding as well as lapping operations.

85 Although I have described in great detail a specific embodiment of my invention, I wish it to be understood that various changes and modifications may be made therein within the scope of the appended claims.

90 It will be noted that the so-called "carrier 12" functions as a main spacer plate for the articles to be lapped, and that the so-called "discs 18" function as secondary spacer plates for the articles to be lapped, and that all of said plates function conjointly in spacing and carrying the articles over the entire 95 lapping surfaces of both lapping discs.

I claim:

1. In a lapping machine, a pair of discs 100 having spaced lapping surfaces, a work carrier between said discs, and means for effecting a relatively oscillatory movement between said carrier and said discs, said carrier being also rotatable about its own center, and said work carrier having a plurality of apertures for loosely holding articles 105 to be lapped, with means for separating a group of the articles being operated upon, said separating means being thinner than the said articles.

110 2. In a lapping machine, a pair of discs having spaced lapping surfaces, a work carrier between said discs, and means for effecting a relatively oscillatory movement between said carrier and said discs, said carrier being also rotatable about its own center, and said work carrier having a plurality of apertures for loosely holding articles 115 to be lapped, with means for holding said articles away from the centers of said apertures, said last mentioned means being thinner than said articles.

120 3. A lapping machine including in combination, two opposed laps having flat working surfaces, a work carrier positioned 125 between said laps and having openings therein for articles to be lapped, each of said openings being of a size to hold a plurality of articles to be lapped, means for effecting bodily movement between the work carrier and laps in a substantially circular path, the 130

said means leaving the work carrier free to rotate about its own axis under the influence of the articles, the plurality of articles in each opening in the work carrier being free to rotate bodily about the axes of the openings so as to execute a substantially planetary movement, and spacing means thinner than said articles and operating to hold apart certain of said articles.

10 4. A lapping machine including in combination, two opposed laps having flat working surfaces, a work carrier positioned between said laps and having openings therein to contain a plurality of articles to be lapped, means for effecting an eccentric motion between said work carrier and laps, said means leaving the work carrier free to rotate about its own axis under the influence of the articles, said openings in the work carrier being smaller than the effective extent of the laps by an amount slightly less than the total eccentricity of the movement between the work carrier and laps, whereby the articles in the openings may overlap the effective working surfaces of said laps and the articles in said openings may rotate bodily about the axes of said openings so as to execute a substantially planetary movement, and spacing means thinner than 20 said articles and operating to hold apart certain of said articles.

25 5. In a lapping machine, two annular laps having flat working surfaces, a main work carrier positioned between said laps and bodily movable therebetween, said carrier having openings, at least one of said openings being of sufficient size to receive a plu-

rality of devices to be lapped, and means for spacing said devices in a ring-like arrangement in said opening, driving means for imparting to the devices to be lapped a revolving motion around the center of the laps, a revolving motion around the center of the carrier, and a revolving motion around the center of said opening, said spacing means 40 being of less thickness than the thickness of 45 the devices being lapped.

6. In a lapping machine, two co-acting lapping discs, a plate between said discs having apertures for spacing articles to be lapped, certain of said apertures being large enough to receive a plurality of such articles, a secondary plate to space said articles in such apertures in the main spacer plate, and means for producing relative 50 movement between said plates and said discs to effect the lapping of said articles, said secondary plate being thinner than the articles being lapped.

7. In a lapping machine, two co-acting lapping discs, a plate between said discs having apertures for spacing articles to be lapped, certain of said apertures being large enough to receive a plurality of such articles, a secondary plate to space said articles in 55 such apertures in the main spacer plate, and means for producing relative movement between said plates and discs to effect the lapping of said articles, said secondary plates 60 spacing said articles in circular arrangement within said apertures in the main spacer plate, and being thinner than the articles being lapped.

JOHN W. SMITH.
